[57] **CLAIM**

The ornamental design for a device for dispensing beverages, as shown and described.

DESCRIPTION

FIG. 1 is a top perspective view thereof;

FIG. 2 is a front elevational view thereof;

FIG. 3 is a rear elevational view thereof;

FIG. 4 is a side view thereof;

FIG. 5 is a top plan view thereof; and,

FIG. 6 is a bottom plan view thereof.

Spigots or bibs at the openings seen in FIGS. 1, 2 and 4, for aid in dispensing beverages, have been omitted for ease of illustration.
